UNITED STATES PATENT OFFICE.

ALBERT L. JOHNSON, OF HAMBURG, NEW YORK, ASSIGNOR TO CORRUGATED BAR COMPANY, OF ST. LOUIS, MISSOURI, A CORPORATION OF MISSOURI.

SECURING-CLIP FOR WALL STRUCTURES.

1,039,136.

Specification of Letters Patent. Patented Sept. 24, 1912.

Application filed September 29, 1911. Serial No. 652,014.

To all whom it may concern:

Be it known that I, ALBERT L. JOHNSON, a citizen of the United States, and a resident of Hamburg, in the county of Erie and State of New York, have invented a new and useful Improvement in Securing-Clips for Wall Structures, of which the following is a specification.

This invention relates to clips for securing metal lathing, and more particularly ribbed or corrugated sheets of expanded metal, to flanged metal studding or rafters and beams, in wall and ceiling constructions.

It has for its principal objects to produce a clip which is applicable for structures employing flanged metal members of practically all the well known commercial sections, including angles, channels, T-irons, I-beams, etc.; to provide for fastening the ribbed or corrugated portion of the lathing to the clips without using additional securing devices; and to attain certain advantages which will hereinafter more fully appear.

The invention consists in the parts and in the arrangements and combinations of parts hereinafter described and claimed.

In the accompanying drawings which form part of this specification and wherein like symbols refer to like parts wherever they occur,—Figure 1 is a fragmentary vertical section through a wall structure comprising studding of angle iron section and ribbed expanded metal lathing, showing an application of my clip; Fig. 2 is a horizontal section taken on the line 2—2 of Fig. 1; Figs. 3, 4, 5 and 6 are detail views of the clip detached, showing it in side and edge elevations; Fig. 7 is a vertical section on the line 7—7 of Fig. 4; Fig. 8 is a horizontal section on the line 8—8 of Fig. 4; Fig. 9 is a fragmentary inner face view of the wall shown in Figs. 1 and 2; Fig. 10 is a horizontal section similar to Fig. 2, showing the studding with its flange disposed edgewise in cooperative relation to the wall; Fig. 11 is a section on the line 11—11 of Fig. 10, on an enlarged scale; and Figs. 12 and 13 are views illustrating the manner in which the clips may be punched from rolled bars.

The clip 1 comprises a body whose marginal portion 2 and two other oppositely disposed marginal portions 2^a are adapted to respectively receive the high ribbed portion of a sheet of metal lathing or the like.

The clip as shown is substantially C-shape; that is, it has a slot in a margin terminating in a hole 7 which is enlarged in both directions from the inner throat of the slot. In other words, the hole 7 extends into the area of the portions 2^a. This obviates the necessity of providing additional openings similar to the hole 6 that is provided in the portion 2 into which the ribbed portion of the lathing in the region thereof is indented, as will hereinafter more fully appear. The arrangement of the hole 7 also gives length to the gripping fingers or jaws 3. The sides of the marginal slot are widened outwardly or rounded, as at 4, so that sharp corners 5 are provided at the inner throat of the slot which is somewhat narrower than the thickness of the flange on which the clip is to be driven. When the clip is driven onto the flange the fingers or jaws grip or take into it with sufficient force to securely hold the clip in place. In order to secure a more stable support for the clip it is provided with a notch or seat 8 at the side of the hole 7 diametrically opposite to the mouth or slot between the jaws 3 and in line with the hole 6 so as to receive the edge portion of the supporting flange.

Referring now more particularly to Figs. 1, 2 and 9, the wall structure comprises studs 9 of angle iron section extending vertically. The clips are driven edgewise onto the flange of the studding which lies parallel with the wall, and the ribbed portion 10 of the lathing is fitted over the beveled portion 2^a of the clip. The metal of the rib which overlies the opening 7 is pressed therein from opposite sides, preferably by a tool having oppositely disposed pins which are movable toward each other and adapted to punch holes in the rib so as to bur or turn the adjacent surrounding metal inwardly. As shown in said Figs. 1, 2 and 9, the studding runs vertically and one of its flanges lies parallel with the walls and the ribs of the lathing run horizontally; but in Figs. 10 and 11, the flange of the stud is turned edgewise to the wall and the rib of the lathing is secured to the portion 2 of the clip which contains the perforation 6. In this case, the metal of the rib is indented or punched into said perforation. In practice, the clips are located where the overlapping ribbed seams of adjoining lathing sheets occur, and at desirable intervals where the ribs intermediate the ends of

the sheets occur, depending upon the number of ribs in a sheet and the distance between them.

Obviously, while the device is shown as applied to side walls, it is also applicable for roofs and ceilings. That is, the roof or ceiling supports or rafters may comprise angle irons arranged as shown in Fig. 10 and the clips secured on the upstanding flange, or the rafters may be arranged as shown in Fig. 2. In other words, with the flange co-operating flatwise with the roof or ceiling, as the case may be. So, too, other flanged metal sections such as channels and I-beams may be substituted for the angle irons which form the studding and rafter. It is further obvious that, instead of the studding being vertically disposed, it may, in some cases, be disposed horizontally and the ribs of the lathing arranged vertically.

The clips may be made by drop forging or as malleable castings, if desired. However, it has been found to be less expensive and, for practical purposes, better to punch them from rolled bars or strips having tapered or beveled side portions corresponding to the desired taper or bevel of the portions 2 and 2^a of the clips, as shown in Figs. 12 and 13. The clips may be punched in the position shown in Fig. 12, in which case only the two portions 2^a of the clip will be tapered; or, as shown in Fig. 13, in which case only the portion 2 and the fingers 3 will be tapered.

Obviously, the clip admits of considerable modification without departing from my invention. Therefore, I do not wish to be limited to the specific construction and arrangement shown.

What I claim is:

1. A clip of the character described comprising a body whose thickness decreases toward one edge and is thereby adapted to fit in a hollow sheet metal rib and having a slot in its margin which slot decreases in width inwardly and terminates in a hole which is enlarged in both directions from the inner throat of said slot such a distance that a portion of the overlying rib may be indented into such enlargement without careful centering, said body also having an addi-

tional hole near the margin opposite the slotted margin.

2. A clip of the character described comprising a body having a slot in the margin thereof converging inwardly and terminating in an enlarged hole which has a notch offset at the back of said hole diametrically opposite said slot, all arranged so that when said clip is mounted on a hollow sheet metal rib the edges of the slot will bind the rib and the notch will prevent transverse displacement. 55

3. A clip of the character described comprising a body portion which has a straight edge and which increases in thickness inwardly from said edge whereby said clip is adapted to fit in the hollow of a sheet metal rib, said body having an enlarged hole extending transversely through it and a slot extending with increasing width from said 70 hole to the edge opposite said first mentioned edge and said hole having a notch offset at the back thereof diametrically opposite said slot, whereby when said clip is mounted on a supporting member the edges of the slot will 75 bind said member and the notch will prevent transverse displacement.

4. The combination with a clip comprising a body having a slot in a margin thereof terminating in a hole which is enlarged transversely from the inner throat of said slot, of a sheet having a high ribbed portion fitted upon said clip, the ribbed portion in the region of said hole being indented into the 80 hole. 85

5. The combination with a clip comprising a body having a slot in a margin thereof terminating in a hole, said body being tapered toward a different margin, of a sheet having a high ribbed portion tapered to conform to 90 the tapered portion of the clip and fitted upon it, the ribbed portion in the region of said hole being indented into the hole.

Signed at St. Louis, Missouri, this 27th day of September, 1911.

ALBERT L. JOHNSON.
